UNITED STATES PATENT OFFICE

166,736

METAL AWNING

Robert A. Childers and Claud C. Miller, Houston,
Tex., assignors to Childers Manufacturing Co.,
Houston, Tex., a corporation of Texas

Application July 27, 1950, Serial No. 11,425

Term of patent 14 years

(Cl. D21—6)

To all whom it may concern:

Be it known that we, Robert A. Childers and Claud C. Miller, both citizens of the United States and residing at Houston, Texas, have invented a new, original, and ornamental Design for a Metal Awning, reference being had to the accompanying drawing, forming part thereof.

In the drawing:

Fig. 1 is a perspective view of a metal awning showing our new design;

Fig. 2 is a front view thereof;

Fig. 3 is an end view thereof, the end not shown being identical with that illustrated; and

Fig. 4 is an enlarged fragmentary view, partly in section taken along lines 4—4 of Figs. 2 and 3, representing the corrugated and crimped formation of the front panel and both side portions of the metal awning shown more particularly in Fig. 1.

The dotted lines shown in Fig. 1 are for illustrative purposes only.

We claim:

The ornamental design for a metal awning, as shown and described.

ROBERT A. CHILDERS.
CLAUD C. MILLER.
